UNITED STATES PATENT OFFICE.

RALPH RAGAN, OF ATLANTA, GEORGIA.

PACKING-RING.

1,106,678.

Specification of Letters Patent. Patented Aug. 11, 1914.

Application filed October 2, 1913. Serial No. 793,030.

To all whom it may concern:

Be it known that I, RALPH RAGAN, a citizen of the United States, residing at Atlanta, in the county of Fulton and State of Georgia, have invented a new and useful Packing-Ring, of which the following is a specification.

The present invention relates to improvements in packing rings, one object of the invention being the provision of a sectional ring adapted to be used in connection with both reciprocating and rotary pistons or valves, and which necessitates the grooving at a single point only of the piston or valve, the sections of the ring being so disposed as to properly pack between the piston and the cylinder so as to prevent the escape of gas or burnt charges in an explosive engine and also the entrance of lubricating oil beyond the head of the piston into the explosion chamber.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

In the drawings—Figure 1 is a sectional view through a portion of an explosion engine cylinder showing the piston with the present piston ring in place thereupon. Fig. 2 is a top plan view of the piston partly in section with the present piston ring in place. Fig. 3 is a perspective view of the complete ring *per se*. Fig. 4 is a section through the ring showing the relative position of the sections thereof. Fig. 5 is a section similar to Fig. 4 of a modified form.

Referring to the drawings, the numeral 1 designates the cylinder which in the present case is the cylinder of an explosion engine, and 2 is a reciprocating piston provided with the circumferential groove 3 adjacent the upper end of the piston. The packing ring 4 is disposed in this groove and is composed of three or more sections, one section 5 being provided with the inclined joint 6 to provide an open ring, and said ring 5 being so disposed as to rest upon the upper edge of the main or lower ring

7 of the packing ring. The ring 7 is cut obliquely as at 8 and when the said rings 5 and 7 are assembled, the open portions 6 and 8 are disposed at diametrically opposite points. A recess or notch 9 is provided in the upper edge of the ring 7 adjacent the cut away portion 8 thereof, while the recessed portion 10 is provided in the lower edge of the ring 5 and forms, as clearly shown in Figs. 1 and 3, a rectangular aperture for the reception of the square head 14 of the locking screw 15. This screw 13 is threaded into the piston 2. The ring 11 is cut at 12 at a point substantially diametrically opposite to the cut 6 of the ring 5, but slightly out of alignment with the cut 8 of the ring 7; and it is also recessed or notched, as the ring 7, to register with the square head 14 of the screw 13. It will be noted that when the rings are assembled, they assume the position, as clearly shown in Figs. 1 and 4, with the lower ring 7 which is of greater width than either of the rings 5 or 11, below both of said rings 5 and 11. By means of the screw pin 13, the sections are held relatively to each other against circumferential movement, while the recess 3 holds the rings against lateral separation.

It will be noted that the ring 7 is what is known as an eccentric expanding ring, and is the main carrying ring of the piston packing, and as clearly shown in Fig. 4, the sections 5 and 11 may be disposed thereabove, or as clearly shown in Fig. 5, additional sections 5^a and 11^a may be disposed therebelow with the ring 7 interposed.

By making the squared end 14 upon the screw 13 terminate within the outer periphery or circumference of the packing ring, its outer end is prevented from scoring the surface of the cylinder during the rotation or reciprocation of the piston, while the recess holds the screw against turning.

What is claimed is:

1. The combination with a piston having a circumferential recess therein, of a packing disposed in said recess and composed of three rings, one of the rings being substantially the same thickness as the two rings combined and the two rings being nested and disposed to rest upon one edge of the thicker ring, the adjacent edges of the three rings at one point being provided with notches that form an aperture, and a screw carried by the piston and insertible in the aperture of the rings to lock the rings

100

110

against independent movement and the complete packing against circumferential movement, the recess and the coöperating portion of the screw being angularly shaped 5 to lock the screw against rotation.

2. The combination with a piston having a circumferential recess, of a packing therefore seated in the recess, said packing being composed of three rings, two of the rings 10 being nested and in combined cross sectional area being substantially the same cross sectional area as the remaining ring, the two nested rings being disposed to fit adjacent one edge of the remaining ring 15 and be disposed in circumferential alignment therewith, all of said rings being open

rings, said rings at one point of contact each being provided with a notch to provide an angular aperture, and means carried within the recess of the piston and projecting in the angular aperture to secure the rings against independent circumferential movement and lock the securing means from rotation. 20

In testimony that I claim the foregoing 25 as my own, I have hereto affixed my signature in the presence of two witnesses.

RALPH RAGAN.
